UNITED STATES PATENT OFFICE.

ARTHUR R. BAKER, OF INDIANAPOLIS, INDIANA, ASSIGNOR TO IRA T. SWARTZ, OF INDIANAPOLIS, INDIANA.

OIL BURNER.

Application filed June 10, 1926. Serial No. 115,121.

My said invention relates to a liquid fuel burner adapted for use in conjunction with furnaces primarily designed for burning solid fuels, but also adapted to be used in furnaces especially designed for burning oil or other liquid fuel.

An object of the invention is to provide an improved atomizing nozzle and simple and effective means for supplying said nozzle with fuel and air, all as will be herein-after more fully described and claimed.

Referring to the accompanying drawings, which are made a part hereof and on which similar reference characters indicate similar parts,

Figure 1 is a side elevation showing the principal parts of my invention,

Figure 2, an end elevation,

Figure 3, a top plan view of the burner, 20 Figure 4, a side elevation of the burner partly in section,

Figure 5, a fragmentary vertical section through the burner,

Figure 6, a section on the line 6—6 of 25 Figure 5, and

Figure 7, a diagrammatic view.

In the drawings reference character 10 indicates a furnace which may be of any desired and appropriate construction, 11 a closure plate for the furnace opening, and 12 a burner mounted on said closure plate. The closure plate 11 is preferably constructed of fire-proof material such as compressed asbestos and is held in position by any desired means as for example bolts 13 having their inner ends engaging openings in the hinge and catch parts for the conventional furnace door and having their outer ends extending through hoods 14 covering the 30 same sections and clamped against the closure plate 11 by means of wing nuts 15. The burner 12 is applied with its end extending centrally through the plate 11. Said burner comprises a body 16 provided 40 with centrally located bore, and with a flange 17 at its forward end for engagement with the plate 11. A shell 18, preferably of brass, extends axially through the cylindrical bore of said body and is provided with threads at its outer or right-hand end (as shown in Figure 5) engaging internal

threads on the body for securing the shell in place. Said shell is provided with a cylindrical intermediate portion cut away at 20 on one end and a reduced cylindrical portion extending from said cut away portion to the end of the shell. The arcuate sections of the shell between the cut away portions snugly engage the interior of a cap or nozzle 19 threaded in the inner end 60 of the body and said reduced cylindrical end portion of the shell is held by said arcuate portions in slightly spaced concentric relation to a flange 21 on said nozzle. The body of the burner is also provided with a passage 22 for admitting air into the cylindrical bore around the shell 18 and the structure is such that air may pass along the cut away surfaces 20 of the shell and between the reduced end of the shell and the flange 21 of the nozzle 19. A second discharge passage 23 forms communication with the space around the shell and a passage 24 which extends from said passage 23 through the flange 17. A valve 25 is provided for varying the size of the opening between the passages 23 and 24, said valve being threaded into the casing and having a locknut 26 for securing it in fixed position. The purpose of said passages 23 and 24 is to by-pass 80 air to reduce the pressure of the air passing through the device and the valve 25 controls the degree of reduction of said pressure. The outer end of the shell 18 is provided with an enlarged opening 27 threaded for the reception of a screw plug 28 which supports the collar 29, of a fuel supply pipe 30, between its head and the head of the shell abutting against the body 16. The screw plug is provided with an annular reduced portion 31 forming an annular passage around the same and one or more openings 32 are provided through said reduced portion and the interior of the screw plug 28 for admitting fuel from the pipe 30 through said passages to the hollow interior of the plug and the shell 18. A valve 33 has a stem 33' extending lengthwise through the shell 18 with a threaded portion engaging internal threads on the screw plug 28. A wing nut 34 is provided for locking the valve in various positions of adjustment for 90 95 100

varying the space between the end of the shell 18 and the conical end of the valve. When the valve is locked in adjusted position the nut 28 carrying the valve stem 33' may be removed and the parts cleaned and replaced with the valve in the same position as it was before being removed. The valve stem is provided adjacent the valve head with a cylindrical portion cut away at 35 to provide passages for oil therethrough the arcuate portions being adapted to maintain it in central position relative to the bore of the shell 18 and said valve head being of a size to snugly engage the inner wall of the shell so that it may be adjusted but is incapable of being distorted by said adjustment. With a valve of this character when the same is adjusted to permit the greatest amount of oil to flow therethrough movement of said valve in axial direction will decrease the supply of oil through the shell 18. On account of the design of the nozzle parts they lend themselves readily to accurate machining thus eliminating the necessity of packed joints.

While I have shown the valve 33 of conical shape, which is desirable for convenience of adjustment, said valve might be constructed of a flat disk that would seat against the end of and close the opening in the shell 18, as will be readily understood. Liquid fuel is supplied to the interior of the shell into the nozzle through pipe 30 and through the passages 32. The passage of the air under pressure through the nozzle creates a suction through the shell and the liquid is sucked out and atomized so that it is very fine and highly inflammable. It will be seen that the air passes in an annular stream through and out of the nozzle and oil will be sucked in a smaller annular stream through the opening around the valve head on account of the creation of a vacuum pocket at the end of the nozzle in front of the end of the valve. The mixing of the oil and air occurs entirely without the nozzle causing all the oil burned to be consumed in suspension and since the ring of air completely surrounds the ring of oil drawn from the nozzle no oil can drip from said nozzle and be wasted. On account of the suction of the air required for drawing the fuel through the nozzle no fuel will pass through until the air has begun to flow therethrough. I have also found that I obtain a quieter combustion by forcing a non-combustible gas such as carbon dioxide instead of air for atomizing the oil and obviously any such gas may be used, however since carbon dioxide is heavier than air it will break up the oil into finer particles and prevent the uniting of air with the sprayed fuel until such sprayed fuel has reached a point of lowered velocity whereupon the point of combustion or the

point at which the fuel is ignited will be spaced at a distance from the nozzle and therefore result in a considerable reduction of the flame noise on account of the reduced velocity of the mixture at the point where combustion occurs.

A pipe 30 extends downwardly into a reservoir 36, formed in the casing for the burner body, said reservoir is provided with pipes 37 and 38 through which oil under pressure may flow into the reservoir 36 and from which reservoir excess fuel may pass back to a pump 39 which causes oil to circulate through the reservoir 36 from supply tank 40. A reticulated screen 41 is preferably disposed in the reservoir 36 between the pipes 37 and 38 to screen the oil before it can enter the pipe 30, however, on account of the arrangement of said screen, if the same becomes clogged, oil may pass over the top of the same and the burner will continue to operate. The burner 12, pump 39 and supply tank 40 are connected in such a manner that oil will be taken in by means of suction to the pump and will be forced from the pump through the pipe 37 to the reservoir 12 from whence the oil which is not consumed may pass by means of the pipe 37 back to the pump 39 and from said pump excess oil will pass through the return pipe 42 to the supply tank 40. The pump here used is a three gear pump, the gears acting as rotary pistons and performing the dual function of supplying the reservoir 12 with fuel from the tank 40 and for returning excess fuel from said reservoir to said tank, said pump being described in my copending application filed June 9, 1926.

The pump 39 may be operated by any desired means, however, in the present instance I have provided a compressor 43 having a base 44 and having a filler and breather opening 45 through which air passes during the operation of the compressor said compressor having a shaft to one end of which the pump is operatively connected and to the other end of which is attached a fly wheel pulley 46 driven by means of a belt 47 from a pulley 48 mounted on the shaft on the motor 49. A tank 62 is kept filled with compressed air by means of the compressor through a connection 63 and the pipe 22 which has one end extending into the air passage into the burner has its other end connected with said compressed air tank.

An idler pulley 50 is supported on a bar 51 which is slidably mounted in an opening in the motor base plate 52 and adapted to be secured in various adjusted positions by means of a set screw 53. A junction box 54 is mounted on the motor base plate 52 closely adjacent the side of the motor, said junction box is provided with a thermal cut-out 55 for breaking the circuit through the

motor and stopping the operation of the pump upon the failure of the atomized fuel to be ignited and heat a thermostat to cause the same to operate a switch to cause the current control to flow through a different line. As shown in Figure 2 the burner 12 is provided with a cap or cover 56 having formed integral therewith a bracket 57 for supporting a housing 58 for a mercury switch 59, said mercury switch being operable by means of a thermostat 60 disposed in front of an opening or window 61 in the closure plate 11.

A cover or belt guard 64 may be provided for preventing foreign objects such as clothing from becoming entangled in the fly wheel pulley of the compressor or in the belt which extends around the same and the pulley of the motor. The guard 64 also covers a number of working parts of the device as well as performing its primary function of preventing objects from becoming entangled in the moving parts of the device.

In the operation of the device current flows from one side of the power line 65 through a room thermostat 75, and through a line 76, junction box 54, and directly through line 77 to one side of the motor 49 and current is supplied from the other side of the power line 66 through the junction box 54 and the line 67 to the intermediate pole of the mercury switch 59. Said mercury switch being in the position shown current will flow from the intermediate pole of the switch, through the pole 68 at the depressed left-end, through the line 69, thermal cut-out 70 and line 78 to the opposite side of the motor and cause the same to operate the compressor 43 and the pump 39 for supplying oil to the burner 12 through the pipe 37 and air to the burner through the pipe 22. The atomized fuel sprayed through the nozzle may be ignited by any suitable device not shown and upon the ignition of said atomized fuel heat will be reflected upon the thermostat 60 which will cause the mercury switch 59 to tilt to its other position opening the circuit through the one end and closing the circuit through the opposite end whereupon the current will flow from the power line 65 through the room thermostat 75 and lines 76 and 77 directly to one side of the motor and through the other power line 66, junction box 54, line 67 through the tube switch lines 72 and 73 to the opposite side of the motor without flowing through the thermal cut-out. In case the atomized fuel does not ignite within the furnace, so that heat will reflect on the thermostat to cause the same to shift the mercury switch, current flowing continually through the thermal cut-out for a certain period of time will cause said thermal cut-out to blow and thus open a circuit through the motor and stop the operation of the compressor and the

pump whereupon it will be necessary to replace or adjust the thermal cut-out before it will again operate.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent, is:

1. An oil burner comprising a body having a cylindrical opening therethrough, a fuel well adjacent the inner end of said cylindrical opening, a screw plug forming a nozzle disposed in the outer end of said opening, a screw plug in the inner end of the opening having a reduced extension projecting through the opening and terminating in the screw plug at the opposite end of the opening and forming an air passage around said extension, means for injecting air into said passage, a hollow plug threaded into said last mentioned plug and having an annular channel around the same and a passage through the wall of said plug connecting said channel with the hollow interior of the plug, a ring for closing said annular channel, a tube threaded through said ring and having its outer end terminating in slightly spaced relation from the bottom of the fuel well, inlet and outlet passages in the said fuel well and a reticulated screen disposed between said inlet and outlet passages whereby fuel may be sucked from said fuel well through said hollow shell by the action of the compressed air around said shell, substantially as set forth.

2. An oil burner comprising a body having a cylindrical opening therethrough, a fuel well adjacent the inner end of said cylindrical opening, a screw plug forming a nozzle disposed in the outer end of said opening, a screw plug in the inner end of the opening having a reduced extension projecting through the opening and terminating in the screw plug at the opposite end of the opening and forming an air passage around said extension, means for injecting air into said passage, a hollow plug threaded into said last mentioned plug and having an annular channel around the same and a passage through the wall of said plug connecting said channel with the hollow interior of the plug, a ring for closing said annular channel, a tube threaded through said ring and having its outer end terminating in slightly spaced relation from the bottom of the fuel well, inlet and outlet passages in the said fuel well, a reticulated screen disposed between said inlet and outlet passages whereby fuel may be sucked from said fuel well through said hollow shell by the action of

the compressed air around said shell, and a valve for controlling the discharge of fuel from said shell, said valve being adjustably mounted in said hollow plug, substantially as set forth.

3. An oil burner comprising a body having a cylindrical opening therethrough, a fuel well adjacent the inner end of said cylindrical opening, a screw plug forming a nozzle disposed in the outer end of said opening, a screw plug in the inner end of the opening having a reduced extension projecting through the opening and terminating in the screw plug at the opposite end of the opening and forming an air passage around said extension, means for injecting air into said passage, a hollow plug threaded into said last mentioned plug and having an annular channel around the same and a passage through the wall of said plug connecting said channel with the hollow interior of the plug, a ring for closing said annular channel, a tube threaded through said ring and having its outer end terminating in slightly spaced relation from the bottom of the fuel well, inlet and outlet passages in the said fuel well, a reticulated screen disposed between said inlet and outlet passages whereby fuel may be sucked from said fuel well through said hollow shell by the action of the compressed air around said shell, a valve for controlling the discharge of fuel from said shell, said valve being adjustably mounted in said hollow plug, and a bleeder passage for reducing the pressure of the air about said shell, substantially as set forth.

4. An oil burner comprising a body having a cylindrical opening therethrough, a fuel well adjacent the inner end of said cylindrical opening, a screw plug forming a nozzle disposed in the outer end of said opening, a screw plug in the inner end of the opening having a reduced extension projecting through the opening and terminating in the screw plug at the opposite end of the opening and forming an air passage around said extension, means for injecting air into said passage, a hollow plug threaded into said last mentioned plug and having an annular channel around the same and a passage through the wall of said plug connecting said channel with the hollow interior of the plug, a ring for closing said annular channel, a tube threaded through said ring and having its outer end terminating in slightly spaced relation from the bottom of the fuel well, inlet and outlet passages in the said fuel well, a reticulated screen disposed between said inlet and outlet passages whereby fuel may be sucked from said fuel well through said hollow shell by the action of the compressed air around said shell, a valve for controlling the discharge of fuel from said shell, said valve being adjustably mounted in said hollow plug, a bleeder pas-

sage for reducing the pressure of the air about said shell, and a valve for said bleeder passage, substantially as set forth.

5. An oil burner comprising a body having a cylindrical opening therethrough, a fuel well adjacent the inner end of said cylindrical opening, a screw plug forming a nozzle disposed in the outer end of said opening, a screw plug in the inner end of the opening having a reduced extension projecting through the opening and terminating in the screw plug at the opposite end of the opening and forming an air passage around said extension, means for injecting air into said passage, a hollow plug threaded into said last mentioned plug and having an annular channel around the same and a passage through the wall of said plug connecting said channel with the hollow interior of the plug, a ring for closing said annular channel, a tube threaded through said ring and having its outer end terminating in slightly spaced relation from the bottom of the fuel well, inlet and outlet passages in the said fuel well, a reticulated screen disposed between said inlet and outlet passages whereby fuel may be sucked from said fuel well through said hollow shell by the action of the compressed air around said shell, a valve for controlling the discharge of fuel from said shell, said valve being adjustably mounted in said hollow plug, a bleeder passage for reducing the pressure of the air about said shell, a valve for said bleeder passage, the plug at the outer end of the cylindrical opening having an internal flange terminating in spaced relation from the reduced end of the shell and said shell having portions engaging the inner end of said hollow plug for holding the same in proper centered relation, substantially as set forth.

6. An oil burner comprising a body having an opening therethrough, a fuel well adjacent the inner end of said opening, a nozzle in the outer end of said opening, a plug in the inner end of the opening having an extension disposed longitudinally within the opening and terminating in the nozzle and forming an air passage around said extension, an inlet passage for admitting air into said air passage, a hollow plug in said last mentioned plug and having a channel therein, and a passage through the wall of the plug connecting the channel with the hollow interior of the plug, a member for closing said channel, a tube extending through said member and having its outer end terminating in the fuel well, and inlet and outlet passages for the fuel well, substantially as set forth.

7. An oil burner comprising a body having an opening therethrough, a fuel well adjacent the inner end of said opening, a nozzle in the outer end of said opening, a plug in the inner end of the opening having an

extension disposed longitudinally within the opening and terminating in the nozzle and forming an air passage around said extension, an inlet passage for admitting air into said air passage, a hollow plug in said last mentioned plug and having a channel therein, and a passage through the wall of the plug connecting the channel with the hollow interior of the plug, a member for closing said channel, a tube extending through

said member and having its outer end terminating in the fuel well, inlet and outlet passages for the fuel well, and means for controlling the discharge of fuel from said body, substantially as set forth.

In witness whereof, I have hereunto set my hand at Indianapolis, Indiana this 28th day of May, A. D. nineteen hundred and twenty-six.

ARTHUR R. BAKER.
